UNITED STATES PATENT OFFICE.

WALTER F. KOKEN AND ANTON J. PICHL, OF ST. LOUIS, MISSOURI.

INTERNAL-COMBUSTION ENGINE.

1,161,220.

Specification of Letters Patent. Patented Nov. 23, 1915.

Application filed October 2, 1913. Serial No. 793,018.

To all whom it may concern:

Be it known that we, WALTER F. KOKEN and ANTON J. PICHL, citizens of the United States, residing at the city of St. Louis, 5 State of Missouri, have invented certain new and useful Improvements in Internal-Combustion Engines, of which the following is a specification.

This invention relates to internal combustion engines of the type in which slide valves are employed for governing the admission and exhaust of the gases to and from the cylinders.

The object of our present invention is to 15 provide a valve-operating mechanism for engines of the type mentioned which is of novel construction and so designed that certain of the valves which control the inlet ports of certain cylinders and the exhaust 20 ports of the remaining cylinders will be moved positively in one direction, while the valves that control the ports not governed by the valves first mentioned are being moved positively in the opposite direction, 25 said mechanism comprising two positively operated members, each of which actuates a group of valves.

Figure 1 of the drawings is a top plan view of an internal combustion engine embodying the present invention; Fig. 2 is a side elevation of same; Fig. 3 is a detail sectional view of one of the reciprocating members; Fig. 4 is a longitudinal sectional view of the cylinders showing an alternative arrangement of the valve-operating means; Fig. 5 is an end elevation of the engine showing an alternative arrangement of the valve-operating means; and Fig. 6 is a side elevation of same.

The cylinders 1, 2, 3, and 4 have the pistons 5 adapted to operate therein, which pistons are connected separately to the cranks (not shown) of the crank-shaft 6 by means of the connecting-rods 7 in the usual manner, said crank-shaft being adapted to rotate in the crank-casing 8 and having the fly-wheel 9 rigidly mounted on one end thereof. Each of said cylinders has an inlet port 10 and an exhaust port 11 in its 45 head, which ports register in vertical alignment with inlet and exhaust passages 12 and 13, respectively, in the cover 14, which is secured to the heads of the several cylinders by bolts 15 or other suitable means. The 50 walls of the passages 12 and 13 project upwardly into a water chamber 16 within the

cover 14, and the top of this chamber is closed by a plate 17, which is secured to said cover by bolts 18 or other suitable means. The inlet passages 12 are separately connected with the branches of the manifold 19, which has the usual connection with the carburetor 20, and the exhaust passages 13 are separately connected with the branches of the exhaust pipe 21. The water-jacket 65 22, which surrounds the cylinders, is communicatively connected with the water-chamber 16 in the cover 14 by means of a pipe 23, which is preferably located at one end of the engine, to allow the water which 70 enters the water-jacket 22 through the inlet pipe 24 to pass into the water-chamber 16, from which it discharges through the outlet pipe 25. A spark-plug 26 and a priming-valve 27 are provided for each cylinder, the 75 spark-plugs being preferably located on one side of the engine and the priming-valves being located on the opposite side.

Communication between the inlet ports 10 and the exhaust ports 11 of the cylinders 80 and their respective inlet passages 12 and exhaust passages 13 is established in proper sequence by means of valves 28, which are adapted to slide horizontally upon the heads of the cylinders and, also, in a groove 29 in 85 the bottom of the cover 14 as shown in Fig. 4. In the case of an engine having four cylinders as illustrated in the drawings, five valves 28 are preferably employed, the two end valves being relatively narrower than 90 the other three intermediate valves. The arrangement of the valves 28 is such that the first or end valve, counting from right to left, Fig. 4, is adapted to slide over and control the exhaust port 11 of the cylinder 95 1, the second valve being adapted to slide over and control the inlet port 10 of the cylinder 1 and the exhaust port 11 of the cylinder 2, the third or middle valve being adapted to slide over and control the inlet 100 ports 10 of the cylinders 2 and 3, the fourth valve being adapted to slide over and control the exhaust port 11 of the cylinder 3 and the inlet port 10 of the cylinder 4, and the fifth or last valve being adapted to slide 105 over and control the exhaust port 11 of the cylinder 4.

The first, third and fifth valves are directly connected together so that they will move in unison and constitute one group of valves 110 which coöperate with all of the cylinders to control the inlet ports of certain cylinders

and the exhaust ports of the remaining cylinders. The second and fourth valves are also directly connected together so that they will move in unison and constitute a second 5 group of valves that coöperate with all of the cylinders to control the ports that are not governed by the group of valves first referred to. The mechanism for actuating said valves consists of two positively operated 10 members, each of which reciprocates one group of valves back and forth, said members being preferably operated directly from the crank shaft of the engine. In the embodiment of our invention illustrated in 15 Fig. 2 a pair of rods 36 are employed for connecting each group of valves to the particular member that operates said group, said member consisting of a lever.

Each rod 36 extends through an opening 20 in one end of the cover 14, and the outer end of the rod bears a member 38, which is preferably bifurcated, the prongs or arms 39 of said member having one end of a pin or rod 40 pivotally attached to and between the 25 same at 41. The free end of said pin or rod 40 is slidably fitted in a longitudinal bore 42 in the upper end of a lever 43, which latter is pivotally attached to and between the outwardly-projecting arms 44 of a bracket 30 45 by a pin 46 or the like, said bracket having a pair of inwardly-projecting arms 47, which arms 47 straddle a lug 48 borne by the cylinder casing and have slots 49 to receive a bolt 50 or a plurality of such bolts, 35 by means of which said bracket is adjustably secured to said lug. Each lever 43 has another longitudinal bore 42 in its lower end, in which the upper end of a pin or rod 51 is slidably fitted. Each pin or rod 51 40 is provided at its lower end with a ball 52 which fits in a socket 53 in a reciprocatory member 54, which is preferably dis-shaped and is slidably supported in a pair of oppositely-disposed grooves 55 in a pair of 45 brackets 56, the latter being arranged in spaced parallel relation and being secured to the crank casing 8 by bolts 57 or other suitable means. Each member 54 bears a 50 downwardly projecting shank 58, the lower end of the latter being preferably bifurcated and having an arcuate blade or shoe 59 riveted or otherwise secured to and between its prongs 60, which blade or shoe is preferably rigid and seats in a cam groove 61, which 55 may be formed either in the periphery of a band 62 rigidly mounted on the fly-wheel 9, or, if desired, in the periphery of the fly-wheel. Each cam groove 61 consists of a right-hand screw-thread groove and a left- 60 hand screw-thread groove, which screw-thread grooves cross at their middle points and connect at their ends so as to make the cam groove continuous, the crossing point of one of the cam grooves 61 being preferably located substantially 180 degrees from

the crossing point of the other cam groove 61. By this arrangement, when the crank-shaft 6 is rotated, the blades 59 travel in the cam grooves 61 and thereby reciprocate the members 54 in the grooves 55 in the brackets 56, whereby said members rock the levers 43, which, in turn, cause the valve-rods 36 to reciprocate the valves 28, with the result of causing the latter to establish communication between the inlet ports 10 and exhaust ports 11 of the cylinders and their respective inlet passages 12 and exhaust passages 13 in the cover 14 in proper sequence.

While we prefer to design the engine so that the power or firing strokes of the pistons 5 occur in the cylinders 1, 2, 3, and 4 in the following order, viz., 1, 3, 4, 2, yet, it should be understood that, the cranks of the crank-shaft may be arranged so that the power or firing strokes of the pistons follow in any other desired sequence, in which event the valves 28 would be so arranged and their movements so timed as to open and close the inlet ports 10 and exhaust ports 11 of the cylinders in the proper order. Furthermore, the engine may have a greater or less number of cylinders, in which case a greater or less number of valves 28 would be employed and would be so arranged and their movements so timed as to open and close the inlet ports 10 and exhaust ports 11 of the cylinders in the proper sequence.

In order to lubricate the valves 28, pipes 63 lead from a receptacle 64, which contains a lubricant, to pipes 65, to the upper ends of which pipes 65 said pipes 63 are connected in any suitable manner, said pipes 65 being preferably located directly above the cylinders 1, 2, 3, and 4, respectively. Each pipe 65 extends through an opening in the plate 17 and has its upper portion screw-threaded to receive a nut 66 or the like, by means of which gasket 67 is held in place to make the junction of said pipe 65 with said plate 17 water-tight, the lower end of said pipe 65 being screw-threaded to fit in a screw-threaded opening 68 in the cover 14, which opening 68 communicates with the groove 29.

Instead of employing levers or rockable members to actuate the valves, the valve rods 36 can be directly connected with the reciprocating members 54, as shown in Fig. 4, or otherwise operated directly from the crank shaft of the engine. In this form of our invention the valve-rods 36 are relatively longer and have their outer end portions bent downwardly, the outer end of each being provided with an enlargement 80 having a screw-threaded opening to receive a pin 51, which is, also, screw-threaded. By this arrangement, the valve-rods 36 are operated directly from the reciprocating members 54, it being, of course, observed that the positions of the blades 59 in the cam grooves 61 are changed so that the valves

28 will open and close the inlet ports 10 and exhaust ports 11 of the cylinders in the proper sequence.

In the alternative arrangement of the 5 valve-operating mechanism depicted in Figs. 5 and 6, the band 62 is provided with only one cam groove 61, and the blades 59 are located diametrically opposite each other in said groove, the members 54 borne by said 10 blades being reciprocatively supported in grooves 55 in separate pairs of brackets 56, which brackets 56 may be secured to the crank-casing 8 by bolts 57 or other suitable means. A bracket 81, having a pair of arms 15 82, which arms straddle a lug 83 borne by the cylinder casing and have slots 84 formed therein to receive a bolt 85 or a plurality of such bolts, by means of which said bracket is adjustably secured to said lug, has a pair 20 of levers 86 pivotally attached thereto by means of a pin or bolt 87 or the like, the upper ends of said levers having longitudinal bores 88 to receive the free ends of the pins 40 and the lower ends of said levers 25 having longitudinal bores 89 to receive the upwardly-turned ends of the pins 51, respectively. By this arrangement, the blades 30 59 travel in the same cam groove 61 and cause the members to reciprocate the valves 28 through the medium of members 54, pins 51, levers 86, pins 40, and valve-rods 36 so as to effect the opening and closing of the inlet ports 10 and exhaust ports 11 of the 35 cylinders in the proper sequence.

From the foregoing it will be seen that a valve mechanism of the construction above described is of simple construction, comprises very few parts and is positive in its operation, the mechanism for actuating all 40 of the valves consisting of only two positively operated members, each of which imparts movement to a separate and distinct group of slide valves, which groups are so designed and arranged that the gases will 45 be admitted to and exhausted from the cylinders in proper sequence.

Various changes in the details of construction and arrangement of parts may be made without departing from the nature and 50 spirit of the present invention.

It should be understood that the portions of the cam grooves 61 where the pitch changes are formed wide enough to permit the blades 59 to travel therethrough.

We claim:

1. In an internal combustion engine, the 55 combination of a cylinder having an inlet port and an exhaust port, reciprocating valves controlling said ports, a device connected to each valve, a pair of rocking members provided with telescoped portions to which said devices are connected, and means for positively actuating said rocking members.

2. In an internal combustion engine, the 60 combination of a cylinder having an inlet port and an exhaust port in its head, reciprocating valves controlling said ports, a rod 65 connected to each valve and having a member pivoted thereto, a pair of rocking members 70 having telescoping connections with said pivoted members, and means operatively connected with the fly-wheel for actuating said rocking members.

3. In an internal combustion engine, the 75 combination of a cylinder having an inlet and an exhaust port in its head, reciprocating valves controlling said ports, a rod connected to each valve and having a member pivoted thereto, a pair of rocking members 80 having telescoping connections with said pivoted members, an adjustable support for said rocking members, and means operatively connected with the fly-wheel for actuating said rocking members. 85

4. In an internal combustion engine, the combination of a cylinder having an inlet port and an exhaust port in its head, reciprocating valves controlling said ports, a rod connected to each valve and having a 90 member pivoted thereto, a pair of rocking members having telescoping connections with said pivoted members, a pair of reciprocating members operatively connected with the fly-wheel, and a pair of members 95 having telescoping connections with said rocking members and, also, ball-and-socket connections with said reciprocating members.

In testimony whereof we hereunto affix 100 our signatures in the presence of two witnesses.

WALTER F. KOKEN.
ANTON J. PICHL.

Witnesses:

H. D. PARRY,
R. E. LONELADY.

It is hereby certified that in Letters Patent No. 1,161,220, granted November 23, 1915, upon the application of Walter F. Koken and Anton J. Pichl, of St. Louis, Missouri, for an improvement in "Internal-Combustion Engines," an error appears in the printed specification requiring correction as follows: Page 2, line 42, for the compound word "dis-shaped" read *disk-shaped*; and that the said Letters Patent should be read with this correction therein that the same may conform to the record of the case in the Patent Office.

Signed and sealed this 14th day of December, A. D., 1915.

[SEAL.]

R. F. WHITEHEAD,

Acting Commissioner of Patents.
